UNITED STATES PATENT OFFICE.

SWITS CONDÉ, OF OSWEGO, NEW YORK.

DESIGN FOR A KNIT FABRIC.

SPECIFICATION forming part of Design No. 14,002, dated June 26, 1883.

Application filed April 25, 1883. Term of patent 7 years.

To all whom it may concern:

Be it known that I, SWITS CONDÉ, of Oswego, in the county of Oswego, in the State of New York, have invented new and useful Improvements in Design for Knit Fabric, of which the following, taken in connection with the accompanying drawing, is a full, clear, and exact description.

This design consists in a novel formation and arrangement of parallel simulating lace-work, as hereinafter more fully described.

The annexed drawing represents a piece of knitted fabric embodying my design.

A A are the parallel stripes, composed of oblique bars a a, which cross each other, so as to form between them diamond-shaped blocks, and project divergently from opposite sides of said blocks, thereby causing said stripes to simulate lace-work.

What I claim is—

The design for knitted fabric, consisting of parallel stripes, composed of oblique bars crossing each other and forming intervening diamond-shaped blocks, and projecting from opposite sides of said blocks, substantially as described and shown.

In testimony whereof I have hereunto signed my name and affixed my seal, in the presence of two attesting witnesses, at Oswego, in the county of Oswego, in the State of New York, this 3d day of April, 1883.

SWITS CONDÉ. [I. S.]

Witnesses:

EDU MAXWELL,
JOSEPH J. REGAN.
